UNITED STATES PATENT OFFICE.

HENRY L. WALLACE, OF WALLINGFORD, CONNECTICUT, ASSIGNOR TO THE
R. WALLACE & SONS MANUFACTURING COMPANY, OF SAME PLACE.

DESIGN FOR A HANDLE FOR SPOONS, FORKS, KNIVES, OR SIMILAR ARTICLES.

SPECIFICATION forming part of Design No. 31,224, dated July 18, 1899.

Application filed June 26, 1899. Serial No. 721,964. Term of patent 7 years.

To all whom it may concern:

Be it known that I, HENRY L. WALLACE, of Wallingford, in the county of New Haven and State of Connecticut, have invented and produced a new Design for a Handle for Spoons, Forks, Knives, or Similar Articles; and I do hereby declare the following, when taken in connection with the accompanying drawing and the letters of reference marked thereon, to be a full, clear, and exact description of the same, and which said drawing constitutes part of this specification, and represents a face view of a handle embodying my design.

This invention relates to a design for a handle for spoons, forks, knives, and similar articles; and the design consists in the configuration and ornamentation shown in the accompanying illustration and hereinafter described.

As herein shown, the handle is substantially plain, expanding slightly at its lower end A,

where it is ornamented on each side by simple scrolls B, then contracts and again expands to form the central portion C of the handle, then curves outward and inward, as at D, and then curves sharply outward and inward, forming the rounded tip E of the handle. This tip E is ornamented by a series of scrolls F, springing from a crowning ornament F' and gradually dying out upon the edges of the tip, all as shown in the accompanying illustration.

I claim—

The design for a handle for a spoon, fork, knife or similar article, as described and shown in the accompanying illustration.

In testimony whereof I have signed this specification in the presence of two subscribing witnesses.

HENRY L. WALLACE.
